TAG FASTENING DEVICE

Carl A. Flood, Framingham, Mass., assignor to
Dennison Manufacturing Company, Framing-
ham, Mass., a corporation of Massachusetts

Application December 30, 1937, Serial No. 182,534

7 Claims. (Cl. 40—22)

This invention relates to devices of the type comprising a tag, a string loop having one end connected to the tag and an elongate retainer joined to the other end of the loop for attaching the loop to fabric or the like by inserting the retainer lengthwise through the fabric from one side and then pulling back on the loop until the retainer seats crosswise against the other side of the fabric, the loop extending from the elongate 10 retainer intermediate its ends so that it can not pull back through the opening in the fabric when seated crosswise against the fabric.

Problems inherent in such devices are to avoid 15 making a substantial opening in the fabric when inserting the retainer and to keep the retainer from pulling back through the opening in the fabric after insertion. These problems have been solved by providing the retainer with a tubular part and having opposite sides of the string loop 20 emerge from opposite ends of the tubular part. Then the retainer need be only large enough in cross-section to encompass one string (instead of two where both ends of the string enter the tubular part from the same end) so that it makes 25 only a very small opening in the fabric when inserted therethrough, and after insertion it automatically tends to resume a position crosswise of the loop so that when the loop is pulled backward the retainer automatically seats against 30 the fabric instead of being pulled back through the opening.

In the case of devices in which opposite sides of the string loop join the retainer at spaced points I have discovered a further difficulty, 35 namely, a tendency for the string loop to widen the opening in the fabric after the device is attached owing to the tendency of the two sides of the loop to pull apart in response to a pull on the tag or other pull on that portion of the 40 loop on the side of the fabric opposite the retainer.

Objects of the present invention are to provide a device of the character referred to which avoids all of the aforesaid difficulties, which produces only a very small opening in the fabric 45 when inserted, which does not become detached from the fabric accidentally, which does not tend to widen the opening in the fabric after it is attached, and which is generally superior to prior devices of the character referred to.

According to this invention one side of the 50 loop extends from the retainer at a point intermediate the ends of the retainer, preferably about midway between the ends, and the opposite side of the loop extends from the retainer at one end

of the retainer or at any other point spaced from the first point lengthwise of the retainer. The two sides of the loop are fastened together at the tag end of the loop in any one of various ways. For example, the loop may pass freely 5 through an opening in the tag with the two sides of the loop clipped together adjacent the tag. However, as hereinafter described, the two sides are preferably fastened together through the medium of the tag itself as by cementing 10 the free ends of the string under a fold or folds of the tag, instead of having the free ends of the string clamped together by the retainer. The preferred method of attachment of the string loop to the retainer is to make the retainer tubular throughout a portion of its length, with 15 the string passing into one end and out the other end of the tubular part, the retainer being clamped around the string tight enough to prevent the string from slipping relatively to 20 the retainer. And the side of the loop extending from the mid-point of the retainer or a point near the mid-point is made shorter than the other side of the loop by an amount at least substantially as great as the distance between 25 the two points where the string joins the retainer, thereby avoiding the tendency to widen the opening in the fabric when the tag is pulled. The shorter side of the loop may join the retainer at any point along the retainer except 30 at the ends of the retainer and the longer side of the loop may join the retainer at any point along the length of the retainer (including the end) which is spaced from the point where the shorter side joins the retainer. Preferably one end of 35 the retainer is pointed and the longer side of the loop joins the retainer at or near its opposite end.

For the purpose of illustration typical concrete embodiments of the invention are shown in 40 the accompanying drawing in which:

Fig. 1 is a perspective view of a partially formed retainer;

Fig. 2 is a similar view of a completely formed retainer clamped around a string loop;

Fig. 3 is a longitudinal section of the retainer and loop;

Fig. 4 is a transverse section through the retainer and loop taken on the line 4—4 of Fig. 2;

Fig. 5 illustrates the application of the finished 50 device to a piece of fabric;

Fig. 6 shows the device after it is applied to the fabric;

Figs. 7 and 8 are similar views of modifications; and

Fig. 9 is a section on line 9—9 of Fig. 8.

The particular embodiment of the invention illustrated in Figs. 1 to 6 comprises a sheet metal retainer 1 having its forward end pointed as indicated at 2. The flat blank used in forming the retainer is preferably uniform in width throughout its entire length except at the pointed end 2. The forward end of the blank is bent transversely into approximately half a cylinder and the rearward end of the blank is bent transversely into approximately a complete cylinder 3. The string loop passes through the cylindrical portion of the retainer and is clamped firmly therein. As shown in Figs. 5 and 6 the free ends 5 and 6 of the string loop enter the tag through an opening 7 and are cemented between the tag body 8 and the folded extension 9. As shown in Fig. 6 the side 11 of the loop which enters the retainer at the end is longer than the side 12 which joins the retainer intermediate the ends of the retainer by an amount slightly greater than the distance between the points where the two sides join the retainer, that is, the length of the tubular portion of the retainer.

25 To apply the device to a piece of fabric 13 the retainer is inserted through the fabric with the pointed end foremost to the position shown in Fig. 5 after which the retainer is pulled all the way through by grasping the pointed end of the retainer. After the retainer has been passed all the way through the fabric the loop is pulled back until the retainer seats against the fabric in the position shown in Fig. 6. In this position the point where the shorter side 12 joins the retainer 35 lies immediately over the opening in the fabric, the longer side of the loop extending through the opening and thence along the opposite side of the fabric to the point where it joins the retainer. Thus a pull on the tag does not tend to separate the sides of the loop from each other as it would if the two sides of the loop were of equal length.

The modification shown in Fig. 7 is like that shown in Figs. 1 to 6 except in that the longer side 22 of the loop joins the retainer 23 at a point intermediate the middle and end of the retainer, in which case the longer side 22 of the loop need not exceed the shorter side so much in length.

The modification shown in Figs. 8 and 9 differs from the other embodiments in two respects. The string is passed through an opening 34 in the tag and the two sides of the loop are fastened together by a metal clip 35, in which case the free ends of the loop may be disposed within the retainer 33 either in end-to-end relationship or in overlapping relationship; and the two sides 31 and 32 of the loop join the retainer approximately equidistantly from the center of the retainer.

From the foregoing it will be evident that the invention is characterized principally by joining the two sides of the loop to the retainer at points spaced from each other lengthwise of the retainer and by making one side of the loop longer than the other so that a pull on the tag does not spread the opening in the fabric. It is also important to fasten the two sides of the loop together at the tag end of the loop to maintain the inequality in the lengths of the two sides of the loop.

It should be understood that the present disclosure is for the purpose of illustration only and that this invention includes all modifications and equivalents which fall within the scope of the appended claims.

I claim:

1. A device comprising a tag, an elongate retainer and a string loop fast to the retainer and

connecting the tag and retainer, one side of the loop extending from the retainer at a point intermediate the ends of the retainer and the opposite side of the loop extending from the retainer at a point spaced from the first point lengthwise of the retainer, said sides of the loop being fastened together at the tag end of the loop and said second side being longer than said first side by an amount at least substantially as great as the distance between said points, whereby when the retainer is inserted through an opening in the fabric and then pulled back against the fabric the longer side may extend along the retainer and thence through the fabric alongside the shorter side without substantial tendency to spread said opening.

2. A device comprising a tag, an elongate retainer and a string loop fast to the retainer and connecting the tag and retainer, one side of the loop extending from the retainer at a point approximately midway between the ends of the retainer and the opposite side of the loop extending from the retainer at a point spaced from the first point lengthwise of the retainer, said sides of the loop being fastened together at the tag end of the loop and said second side being longer than said first side by an amount at least substantially as great as the distance between said points, whereby when the retainer is inserted through an opening in the fabric and then pulled back against the fabric the longer side may extend along the retainer and thence through the fabric alongside the shorter side without substantial tendency to spread said opening.

3. A device comprising a tag, an elongate retainer and a string loop fast to the retainer and connecting the tag and retainer, the retainer having a tubular part at least one end of which is intermediate the ends of the retainer, one side of the loop extending from said end of the tubular part and the opposite side of the loop extending from the other end of the tubular part, said sides of the loop being fastened together at the tag end of the loop and said second side being longer than said first side by an amount at least substantially as great as the length of said tubular part, whereby when the retainer is inserted through an opening in the fabric and then pulled back against the fabric the longer side may extend along the retainer and thence through the fabric alongside the shorter side without substantial tendency to spread said opening.

4. A device comprising a tag, an elongate retainer and a string loop fast to the retainer and connecting the tag and retainer, the retainer having a tubular part one end of which is approximately midway between the ends of the retainer, one side of the loop extending from said end of the tubular part and the opposite side of the loop extending from the other end of the tubular part, said sides of the loop being fastened together at the tag end of the loop and said second side being longer than said first side by an amount at least substantially as great as the length of said tubular part, whereby when the retainer is inserted through an opening in the fabric and then pulled back against the fabric the longer side may extend along the retainer and thence through the fabric alongside the shorter side without substantial tendency to spread said opening.

5. A device comprising a tag, an elongate retainer and a string loop fast to the retainer and connecting the tag and retainer, one side of the loop extending from the retainer at a point ap-

proximately midway between the ends of the retainer and the opposite side of the loop extending from the retainer at one end of the retainer, said sides of the loop being fastened together at 5 the tag end of the loop and said second side being longer than said first side by an amount at least substantially as great as the distance between 10 said points, whereby when the retainer is inserted through an opening in the fabric and then 15 pulled back against the fabric the longer side may extend along the retainer and thence through the fabric alongside the shorter side without substantial 20 tendency to spread said opening.

6. A device comprising a tag, an elongate retainer and a string loop fast to the retainer and connecting the tag and retainer, the retainer having a tubular part one end of which is approximately midway between the ends of the retainer and the other end of which is at one end of the 25 retainer, one side of the loop extending from said first end of the tubular part and the opposite side of the loop extending from said second end of the tubular part, said sides of the loop being fastened together at the tag end of the loop and said second side being longer than said first side by an amount at least substantially as great as the length of said tubular part, whereby when

the retainer is inserted through an opening in the fabric and then pulled back against the fabric the longer side may extend along the retainer and thence through the fabric alongside the shorter side without substantial tendency to 5 spread said opening.

7. A device comprising a tag, an elongate retainer and a string loop fast to the retainer and connecting the tag and retainer, the retainer having a tubular part at least one end of which 10 is intermediate the ends of the retainer, one side of the loop extending from the retainer at the forward end of the tubular part and the opposite side of the loop extending from the retainer at the rearward end of the tubular part, said 15 sides of the loop being fastened together at the tag end of the loop and said second side being longer than said first side by an amount at least substantially as great as the length of said tubular part, whereby when the retainer is inserted 20 through an opening in the fabric and then pulled back against the fabric the longer side may extend along the retainer and thence through the fabric alongside the shorter side without substantial tendency to spread said opening. 25
